His Atty.

UNITED STATES PATENT OFFICE.

HEYMAN ROSENBERG, OF NEW YORK, N. Y.

HAND-PUNCH.

1,324,621.

Specification of Letters Patent.

Patented Dec. 9, 1919.

Application filed May 19, 1919. Serial No. 298,049.

To all whom it may concern:

Be it known that I, HEYMAN ROSENBERG, a citizen of the United States, residing at New York, in the county of New York and 5 State of New York, have invented certain new and useful Improvements in Hand-Punches; and I do hereby declare the following to be a full, clear, and exact description of the invention, such as will enable 10 others skilled in the art to which it appertains to make and use the same.

The present invention relates to hand punches, and has for an object to provide an improved construction of socket coupling 15 or holder for punch points admitting of the use of a series of punch points varying in size or character with a single punch frame and its operating mechanism.

Another object is to provide an improved 20 coupling in a hand punch which may be used in the punch frames of ordinary construction and size without altering the same and which may accommodate punch points of various sizes and operate the same by the 25 ordinary manipulation of the punch.

With these and further objects in view as will in part hereinafter become apparent and in part be stated, the invention comprises certain novel constructions, combinations and arrangements of parts as subsequently specified and claimed.

In the accompanying drawing,—

Figure 1 is a side elevation of a present-used hand punch having the improved point 30 holder of this invention applied thereto.

Fig. 2 is a vertical section taken through the head of the punch substantially on the line 2—2 of Fig. 1.

Fig. 3 is a fragmentary, side elevation, 40 partly in section, of the head of the hand punch showing the operating lever thrown over for withdrawing the punch point and its socket ready for detaching the point.

Fig. 4 is a detail, enlarged view showing 45 the parts of the socket and the punch, the same being separated.

Referring to the drawing by numerals, 50 10 designates the frame of a punch provided in the usual manner with upper and lower jaws 11 and 12, the latter carrying the removable die 13 in the usual manner, and the upper jaw 11 having a bore 14 therein in axial alinement with the die 13. The upper portion of the jaw 11 is counter-bored to 55 provide a chamber or way 15 and has an upwardly flaring recess or groove 16 at the

inner side of the chamber 15 to facilitate removal of the punch point from the upper jaw when the handle is thrown over, as shown in Fig. 3.

The frame 10 carries at opposite sides of the upper jaw 11 a pair of links 17 pivoted at their lower ends upon trunnions or projections 18 of the frame, in the usual manner, and carrying between their upper ends the ordinary handle 19, the handle 19 having an offset 20 at its inner end which is forked and receives therebetween the head 21 of the punch point socket.

This socket comprises a threaded reduced 70 stud 22 formed on the under side of the head 21 and adapted to receive in threaded engagement thereover a coupling piece 23 provided interiorly with a relatively deep chamber 24 and a co-axial opening 25 which passes 75 through the lower end of the coupling member 23. A punch point is shown at 26, and has a head 27 adapted to fit in the chamber 24 of the coupling member and to be clamped therein by the lower end of the 80 stud 22 when the coupling member 23 is turned up over the stud. The shank of the punch point 26 passes through the bore or opening 25 and projects below the socket for passage through the opening 14 in the upper 85 jaw 11. The lower end of the punch point 26 may be of any suitable size and form within the limits of the diameter of the shank or stem of the punch point and is adapted to coöperate with the die 13, the 90 latter being removable to permit the mounting of other dies in the lower jaw 12, should it be found necessary to interchange the dies 13 to correspond with the punch point 26 used.

The head 21 of the socket has a lip 28 95 adapted to be engaged by a pivoted locking member 29 when the handle 19 is raised in the ordinary operation of the punch. The locking member 29 may be turned into the 100 position shown in Fig. 2 to release the head 21 and admit of the throwing over of the handle 19 to withdraw the socket and the punch point from the upper jaw 11, and to position the same for easy access for the 105 removal or interchange of the punch point 26.

It is apparent that a set or series of punch points 26 may be used with a single punch and the points may be interchanged to accommodate the punch to various classes of work to which the hand punch is adapted.

The invention thus provides a means whereby a simple hand punch may be employed for forming punch holes of different sizes and shapes, and the separable socket 5 is of the above-described peculiar construction with its exterior cylindrical surface of uniform diameter and length corresponding to the ordinary punch socket now employed, so that the new separable socket may be 10 used in the ordinary punch frame without any alterations or additions thereto.

When it is desired to interchange a punch-point 26, it is only necessary to throw the handle 19 over for withdrawing the punch 15 point and its socket, as shown in Fig. 3. The coupling piece 23 is now grasped by the fingers, pliers, a wrench, or the like at its gripping faces 30 for unscrewing the coupling piece from the stud 22. By inverting 20 the coupling piece 23 the punch point 26 may now drop out of the coupling piece and a different punch point may be inserted. The coupling piece 23 is now screwed up 25 upon the stud 22 and the new punch point is held firmly in position. As shown in Figs. 1, 2 and 4, particularly, the lower portion 30 of the head 21 and the coupling piece 23 are of the same external diameter to admit free passage of the socket into the opening 15 in the top of the upper jaw 11.

I claim:—

1. In a punch, the combination with a frame having upper and lower jaws with a passage in the upper jaw for receiving a 35 punch point and its socket, and a handle operatively mounted upon the frame, of a socket having a head mounted on the handle and provided with a threaded stud, and a coupling piece threaded upon the stud 40 adapted to bind against the head and having a chamber therein to receive the head of a punch point and an opening in its end through which the stem of the punch point is adapted to pass.

2. In a punch, the combination with a 45 frame, a handle on the frame, and a die mounted on the frame, the upper portion of the frame having the usual chamber in axial alinement with the die, a separable socket carried by the handle and having a chamber 50 therein and an opening leading from the chamber through the end of the socket, said socket being adapted to removably support a punch point with the head of the point in the chamber and the stem of the point removably fitting in the opening to project beyond the socket and enter said chamber in the upper part of the punch frame. 55

3. In a punch, the combination with a frame having upper and lower jaws and a 60 chamber in the upper jaw opening therethrough toward the lower jaw, a handle pivoted on the frame, and a punch point adapted to enter the opening in the upper jaw, means for detachably connecting the 65 punch point to the handle, said means comprising a socket head adapted to be pivotally mounted upon the handle and having a reduced portion to enter the opening in the upper jaw and a further reduced threaded 70 stem, a coupling piece having an interior chamber and threaded at one end to engage the stud and having a reduced opening at its other end for receiving the stem of the punch point, said coupling piece being adapted 75 to be turned up upon the stud for binding the head of the punch point in the bottom of the chamber, the first reduced portion of the head and the coupling piece being of like external diameter for free passage into 80 and out of the opening in the upper jaw.

In testimony whereof I affix my signature in presence of two witnesses.

HEYMAN ROSENBERG.
